UNITED STATES PATENT OFFICE.

JOHN F. GILLAN, OF SCHENECTADY, NEW YORK, ASSIGNOR TO GENERAL ELECTRIC COMPANY, A CORPORATION OF NEW YORK.

METAL-TREATING APPARATUS.

1,425,851.

Specification of Letters Patent. Patented Aug. 15, 1922.

Application filed October 2, 1920. Serial No. 414,195.

To all whom it may concern:

Be it known that I, JOHN F. GILLAN, a citizen of the United States, residing at Schenectady, in the county of Schenectady, 5 State of New York, have invented certain new and useful Improvements in Metal-Treating Apparatus, of which the following is a specification.

The present invention comprises an improved apparatus for carrying out metal coating processes, and particularly the process known as sherardizing, which involves the surface alloyage of a metal with zinc.

Sherardizing was first carried out in large 10 gas heated ovens adapted to receive rotatable drums containing the sherardizing mixture and the articles to be treated. Later it was found that improved results could be obtained as described in U. S. Patent No. 20 1,169,529 granted to Collins and Capp January 25, 1916 by correlating the composition of the charge and the sherardizing temperature. It was found that by the use 25 of electrically heated drums the desired temperature range could be attained with greater speed and maintained with greater accuracy. The alloyage produced at proper temperatures is markedly superior to the 30 alloyage produced outside of this optimum temperature range.

In accordance with my present invention, I have increased the efficiency of the individually heated sherardizing drum and reduced the cost of sherardizing by providing 35 the rotatable drum with one or more removable containers fitted to revolve as a part of the rotatable drum, thereby still further reducing the time required to raise the temperature of the charge to the required 40 optimum range and also facilitating the loading and unloading of the charge.

The accompanying drawing illustrates in a disassembled view an embodiment of my invention.

45 In perspective are shown by Fig. 1 the rotatable drum; by Fig. 2 a removable container; by Fig. 3 an electrically heated cover; and by Fig. 4 a suitable clamping device therefor.

50 The heated drum illustrated in Fig. 1 comprises a receptacle 1 supported on trunnions 2, 3 and provided with a suitable rotating means as, for example, the worm drive 4. The receptacle 1 is double-walled, 55 a suitable electric heater 23 being provided

between the outer wall 5 and inner wall 6. Electric current is conveyed to this heater by the conductors 7, 8, 9, connected to the brushes and slip rings 10, 11 and 12. Suitable contacts (not shown) convey the current to the resistor located within the cover 17 (Fig. 3). A container 13, (Fig. 2), is proportioned to fit fixedly within the receptacle or drum 1. The container 13 has a removable cover 14 provided with locking 60 devices 15. The cover 14 of the receptacle 13 may be handled by the ring-shaped 65 holders 16 through which a hook of a lifting device may be passed while the container and its charge may be readily handled by hooking into the folding lugs 16' which are attached to its ends, as shown in Fig. 2. Within the container 13 may be placed a charge of iron or steel articles to be treated and a sherardizing mixture 70 consisting say of about 85 parts powdered zinc and about 15 parts zinc oxide.

When the container 13 is placed within the heated receptacle 1 the cover 17 may be fastened in place by the clamping bars 18, 80 19, the ends of which project through the slots in the lugs 20, carried by the container 1 and projecting through holes in cover 17. The bars 18, 19 are adapted to be held in place by suitable bolts 21. Ring bolts 22 85 are provided for lifting the cover 17. The sherardizing process is carried out as usual while rotating the apparatus and heating to a temperature of about 350 to 375° C.

In practice, two or more inner containers 90 may be provided so that when one charge has been subjected to the treating temperature for a sufficient length of time, the container 13 may be removed while the housing 1 is still hot and another charged container 95 may be immediately substituted, the cover 17 replaced and the sherardizing process continued. Two advantages are thus gained, first, the fresh charge in the container 13 is brought more rapidly to the desired sherardizing temperature as the outer housing is already hot; secondly, the time is saved as the hot container when removed may be permitted to cool off without interfering with the other steps of the process. As a 100 result of my invention, sherardizing is improved and rendered more uniform and the capacity of a given apparatus is more than doubled.

What I claim as new and desire to secure 110

by Letters Patent of the United States, is:—

1. A metal treating apparatus comprising the combination of a rotatable container, a closure for the same, means for heating said container, a receptacle fitted within said container but removable therefrom.
2. A sherardizing apparatus comprising the combination of a rotatable container comprising a plurality of fitted separable receptacles one of which constitutes a housing and an electric heater fixedly connected with said housing.
3. A sherardizing apparatus comprising the combination of a rotatable container, a heater therefor, and a removable receptacle nested within said rotatable container.
4. A sherardizing apparatus comprising the combination of a receptacle, means for

rotating the same, heating means for said receptacle, a second receptacle having a 20 shape substantially corresponding to the interior configuration of said first receptacle, and closures for said respective receptacles.

5. A sherardizing apparatus comprising the combination of a double walled receptacle, an electric heater arranged between the walls of said receptacle, a removable cover for said receptacle, means for rotating said receptacle a second receptacle adapted to be fixedly nested within said first receptacle and holders attached to said second receptacle whereby the same may be removed from said first receptacle.

In witness whereof, I have hereunto set my hand this first day of October, 1920.

JOHN F. GILLAN.
